UNITED STATES PATENT OFFICE.

SUMNER A. BEMIS, DECEASED, LATE OF SPRINGFIELD, MASSACHUSETTS, BY ELLA M. BEMIS, EXECUTRIX, OF SPRINGFIELD, MASSACHUSETTS.

TROLLEY.

1,069,519.

Specification of Letters Patent.

Patented Aug. 5, 1913.

Application filed October 12, 1910. Serial No. 586,786.

To all whom it may concern:

Be it known that SUMNER A. BEMIS, deceased, late a citizen of the United States of America, and resident of Springfield, in the county of Hampden and State of Massachusetts, did invent certain new and useful Improvements in Trolleys, of which the following is a full, clear, and exact description.

This invention relates to trolleys for electric railway cars and pertains to improvements in the trolley wheel, the manner of its mounting and lubrication in the head, and to improvements in the form of head comprising a fixed jaw having an axle stud and a hinged jaw which opens and closes relatively to the fixed jaw whereby the trolley wheel may be readily placed in or removed from the head without the necessity of removing the axle stud, and to improved constructions and arrangements for detachably holding the contact springs in their proper positions in the trolley head.

The invention is described in conjunction with the accompanying drawings and is set forth in the claims.

In the drawings:—Figure 1 is a sectional vertical view through the trolley as taken on the plane of the axis of the trolley wheel. Fig. 2 is a vertical sectional view of the trolley on line 2—2, Fig. 1. Fig. 3 is a perspective view of the fixed jaw of the trolley head, the axle fixedly supported thereby and the bushing for the axle shown as removed from the latter. Fig. 4 is an elevation of the trolley at the side thereof at which the hinged jaw is located. Fig. 5 is a horizontal cross section on line 5—5 Fig. 1. Fig. 6 is a perspective view of the hinged or movable jaw of the trolley head and showing one of the contact springs as in readiness to be placed in engagement therewith.

Similar characters of reference indicate corresponding parts in all of the views.

In the drawings, A represents the fixed jaw of the trolley head, and B the hinged and movable jaw. The fixed jaw is formed integrally with and upwardly extended from the shank C of the head which comprises opposite side walls a a which are arranged right angularly to the general plane of the fixed jaw. The movable jaw has at its lower portion opposite ear lugs b b which are matched facewise relatively to the opposite side walls a a of the shank, and the pivot

stud d extends through the ear lugs b b and walls a a and has the ends thereof upset or riveted. One of the aforementioned ear lugs b, as shown in Figs. 1 and 5, is extended inwardly beyond the pivot stud d and has a perforation e therethrough matching with a perforation e which is provided in the adjacent side wall a of the shank; and a cotter pin f or other appropriate pin has a locking engagement through the said perforations for detachably confining the hinged jaw in its closed position as shown. The fixed jaw has a transverse hole g through the upper portion thereof and the oppositely located hinged jaw has a transverse inwardly flaring hole g² through its upper portion.

The axle-stud D has a head or enlargement h at one end and its other end portion i is tapered; and the said stud is engaged with a driving fit through the hole g in the fixed jaw so that its head is brought against the outer side of such head and such stud is adapted by its tapered end to have an engaging fit in the flaring hole g² of the movable jaw. The said movable jaw has a hole j through its upper portion transversely of the free end of the axle stud, and to align with a hole j² in such extremity so that when the parts are in their closed and interlocked relations they may be additionally confined by the cotter pin k.

The fixed jaw A has a lug m at its inner side adjacent the hole through which the axle stud is passed; and F represents a bushing sleeve which has recesses n n in its opposite ends whereby one end thereof may be in engagement with the said lug m so that the sleeve will be prevented from turning on the axis stud, or whereby if the bushing is endwise reversed it may be by its opposite recessed end in the rotation presenting engagement with the said lug; and by having the recesses duplicated and in opposition at each end of the bushing, provision is made for changing the relative position of the latter a half a rotation,—all to the end of providing changes of position for the bushing for compensation for wear.

The trolley wheel G has a chamber o in its body for the reception of a lubricant, and such body is made with an annular mouth q inwardly opening to the central hole through the trolley wheel for the delivery of lubricant onto the central portion of the bushing F, which, as represented in

Figs. 1 and 3, is grooved at its intermediate portion, as indicated by the letter *s*.

Each jaw at its lower or shank portion and at its inner side is made with an integrally formed boss *t* against the inner end or face of which is placed the end portion of a flat spring plate *u*, such extremity being secured by a rivet *u*². Said spring plate extends upwardly from its rivet connected extremity, is bent around toward the face of the jaw and downwardly returned in its other end portion which constitutes a spring tongue *u*³, and which latter has a reaction toward the inner face of the jaw.

It is to be noted that the jaw adjacent the return bent portion of the said spring plate is made with an integrally formed guide lug *v*; and for the accommodation of such lug the spring plate at its upper return bent portion is provided with an aperture *w* so that the spring will not, in any manner, by the lug, be interfered with for its spring reaction toward the inner side of the jaw.

The contact spring provided at each side of the jaw in the usual situation relatively to the axis and hub end of the trolley wheel has its lower portion made of a forked shape; and the spring, while reliably retained in its place in the trolley head when forced down between the spring tongue *u*³ to the inner face of the jaw and as guided and centered by the lug *v*, may be most easily withdrawn from its place in the head, without the requirement of removing any rivets, screws or like fastenings for the quick replacement thereof.

What is claimed is:—

1. A trolley head comprising at one side an integrally formed upwardly extending fixed jaw, provided with an axle stud rigidly supported and transversely horizontally extended therefrom, said axle stud having a small perforation transversely through it near its free end, and said jaw having at its shank portion opposite side walls which are arranged right angularly to the general plane of said fixed jaw, and a movable jaw having at its lower portion opposite ear lugs which are matched facewise relatively to the aforesaid opposite side walls of the shank, a pivot stud extending through said opposite ear lugs and the shank walls adjacent thereto, one of said ear lugs being extended inwardly beyond said pivot stud and having a perforation therethrough, matching with which is a perforation which is provided in the adjacent side wall of the shank, a pin for detachably locking through said perforations,—and the said movable jaw having a hole transversely through its upper portion for engagement with the free

end of the axle stud, having another, and smaller, hole intersecting the first named one and for matching with the comparatively small hole which is provided in the extremity of the axle stud.

2. A trolley head and a contact spring therefor, the head comprising opposite upstanding jaws and having a wheel supporting axle mounted in the upper portion thereof, the shank portions of the said jaws having at the inner walls thereof each a spring formed of thin flat metal bent into loop form, the lower extremity thereof being secured to the wall and extending upwardly from its secured portion in spaced relation to the wall while a return bent and downwardly extended portion of the spring plate which has its location inside of the aforesaid secured lower extremity, and terminates above the securing point, is adapted for a spring reaction toward the face of the wall, and acts to impart a yielding retaining force against the shank of the contact spring which is readily insertible between the aforesaid return bent and downwardly extended spring portion and the said wall.

3. A trolley head having at the lower portion of its jaw an inwardly extending guide lug, and a flat spring plate by its extremity secured to the inner side of the jaw below said lug, the same being upwardly extended from its secured portion inwardly return bent to constitute a downwardly returning spring tongue adapted for a reaction against the inner face of the jaw and having a recess in its upper portion for the accommodation of the said guide lug therein.

4. A trolley head having in the lower portion of its jaw an inwardly extending guide lug, a flat spring plate by its extremity secured to the inner side of the jaw below said lug, the same being upwardly extended from its secured portion, bent around toward the face of the jaw and downwardly returned, and having at its upper return bent portion a recess for the entrance thereinto of said guide lug, and a contact spring the lower end of which is forked and adapted upon having a guiding engagement with said lug between the wall of the jaw and the said spring tongue to be tensioned and reliably held in place by the latter.

Signed at Springfield, Mass., in presence of two subscribing witnesses.

ELLA M. BEMIS,
*Executrix of the last will and testament of
Sumner A. Bemis, deceased.*
